MACHINE FOR MANUFACTURING HAT LININGS.

No. 593,702.

Patented Nov. 16, 1897.

UNITED STATES PATENT OFFICE.

WILLIAM HENRY THOMAS, OF FALL RIVER, MASSACHUSETTS.

MACHINE FOR MANUFACTURING HAT-LININGS.

SPECIFICATION forming part of Letters Patent No. 593,702, dated November 16, 1897.

Application filed December 31, 1896. Serial No. 617,641. (No model.)

To all whom it may concern:

Be it known that I, WILLIAM HENRY THOMAS, a citizen of the United States, residing at Fall River, in the county of Bristol and State of Massachusetts, have invented certain new and useful Improvements in Machines for Manufacturing Hat-Linings; and I do hereby declare the following to be a full, clear, and exact description of the invention, such as will enable others skilled in the art to which it appertains to make and use the same.

This invention relates to machines for manufacturing and shaping hat and bonnet linings, so that the same will conform closely to the contour of the inside of the hat or bonnet, thus obviating the necessity for cutting and stitching the material from which the lining is formed and shaping the same by hand to fit the hat.

The invention consists in certain novel features and details of construction and arrangement of parts, as hereinafter fully described, illustrated in the drawings, and embodied in the claims.

In the accompanying drawings, Figure 1 is a side elevation of a machine constructed in accordance with the present invention. Fig. 2 is a plan view of the same. Fig. 3 is an enlarged side elevation of the rotatable holder upon which the lining material is placed and held while subjected to the action of the crimping-rolls. Fig. 4 is a longitudinal section through the same. Fig. 5 is a detail perspective view of the plate upon which the lining is placed. Fig. 6 is a similar view of the opposing plate, which overlies the lining material. Fig. 7 is a detail perspective view of the eccentrically-movable head upon which the supporting-plate is mounted. Fig. 8 is a plan view of the stationary disk about which the head moves, and Fig. 9 is a perspective view of the hat-lining after the same has been crimped by the improved machine.

Similar numerals designate corresponding parts in the several figures of the drawings.

Referring to the drawings, 1 designates the bed-plate of the machine, to which are secured a pair of spaced rigid standards or arms 2, the upper ends of which are extended vertically upward and downward to form slotted guides 3, in which are mounted threaded rods or shafts 4, journaled at their upper and lower

ends in bearings 5, located at the upper and lower ends of said guides.

6 designates a cross-head which has its ends reduced and slidably fitted in the grooves of the guides 3, so that it may move up and down therein, said cross-head being adjusted by turning the rods or shafts 4, which have a threaded engagement with the ends of the cross-head or with sleeves or ferrules fitted thereon. The cross-head 6 is provided at or near its center with a cross sleeve or socket 7, through which passes an inclined or oblique shaft 8, having movably fitted upon its lower end one of the crimping-rolls 9, which is preferably convex on its outer surface and milled or provided with corrugations, as indicated at 10, said corrugations meshing with corresponding ribs or corrugations 11 on a concave crimping-roll 12, movably fitted on the end of a horizontal shaft 13. A tension-spring 14 is interposed between a collar 15, fitting loosely around the shaft 8 and seated in an annular groove therein, and one of the guides 3 or a cross-bar connecting said guides, as may be most convenient, the tension of said spring being exerted to preserve the proper engagement between the crimping-rolls, while the corrugations of said rolls may be adjusted into proper mesh with each other by raising or lowering the cross-head 6.

14' indicates a pendent rod which connects pivotally with the upper end of the shaft 8 and at its lower end with a lever fulcrumed on one of the standards 2. By rocking said lever the upper roll 9 may be lifted out of contact with the lower roll for introducing or removing the lining material. The shaft 13 is hollow and the rear end of said shaft receives the discharge end of a Siamese pipe 16, which conveys gas and air to said shaft and through the same into the crimping-roll 11, which is hollow and forms a combustion-chamber in which the gas is ignited for heating said roll to the desired temperature. The lining material is sized with any suitable agent upon one surface, and when subjected to the action of the crimping-rolls the flutes or crimps made therein are rendered more permanent than would be the case were such material simply passed between cold rolls. The rolls 9 and 12 are provided at their inner and outer

edges, either or both, with matching annular beads 17 and grooves 18, whereby the lining material is beaded at the inner or outer portions of the crimps or at both ends, thereof as 5 may be preferred.

19 designates the supporting-plate for the lining material, said plate being substantially elliptical in plan view and provided with depressed sockets 20, in which are fitted pieces 10 of cork or other soft material to receive the depending points or spurs 21 of an upper opposing elliptical plate 22, adapted to be placed on the lining material, so that the pins or spurs will pass therethrough into the lower 15 plate, the upper plate being provided with a finger-hold or handle by means of which it may be removed and replaced. Secured to the under side of the supporting-plate 19 is a head 24, having spaced arms 25, by which 20 it is secured to the plate 19, and having spaced depending flanges 26, the purpose of which will appear. 27 represents a stationary disk upon which said head is mounted, and this disk is provided with a radial slot 25 28, up through which projects a pin or stud 29, fast on one end of a slide-bar 30, mounted in a grooved guide 31, secured to and supported upon the bed-plate in any convenient manner. The pin or stud projects above the 30 upper surface of the disk 27 and enters a slot 32 in the body portion of the head, said slot 32 extending transversely of the elliptical supporting-plate 19.

33 designates a pair of keeper-plates which 35 are secured to the bottom of the depending flanges of the bearing-head, said plates being extended under the stationary disk and serving to prevent the displacement of the bearing-head from said disk as the supporting- 40 plate is revolved.

By means of the construction just described the supporting-plate 19 when revolved will have an eccentric motion, so that the edge which lies adjacent to the crimping-rolls will 45 be maintained at the same distance therefrom, thus enabling the crimping-rolls to operate upon and flute the projecting edge of the lining material in an elliptical path. This eccentric motion is caused by the coöperation of 50 the stud 29 with the slot in the bearing-head. Where it is desired to substitute a supporting-plate 19 of different size or shape, the said stud may be adjusted lengthwise of the slot in the stationary disk by moving the slide-bar 30. The outer end of the slide-bar is provided with a longitudinal slot 35, through 55 which passes a screw 36, said screw entering the guide in which the slot is mounted.

37 designates a washer which is interposed 60 between the head of the screw and the slide-bar, and which is provided with a depending portion 38, entering the slot in the slide-bar, and also with an upturned portion 39 at the opposite end of the head of the screw. By 65 loosening this screw the slide may be adjusted for changing the position of the pin or stud at the opposite end of said bar.

The piece of material from which the hat-lining is to be formed is engaged between the elliptical plates above described, and the upper crimping-roll is lifted to admit the marginal edge of the lining between the rolls. The machine is now actuated either by hand 70 or some suitable motor, thus causing the crimping-rolls to grip the lining material, and as the material feeds between the rolls the supporting-plate is revolved, and by reason 75 of its eccentric movement the edge of the supporting-plate is kept at a uniform distance from the rolls, thus crimping the lining material in elliptical form, as shown in the drawings. This rolls the marginal edge of the lining over, as shown in the drawings, and adapts 80 it to conform closely to the inside contour of the hat. Any desired fabric or soft material 85 may be employed in the manufacture of the hat-lining and will be crimped with uniform success by the machine above described.

It will be understood that several parts of the machine are susceptible of changes in the 90 form, proportion, and minor details of construction, which may accordingly be resorted to without departing from the spirit or sacrificing any of the advantages of the invention.

Having thus described the invention, what 95 is claimed as new, and desired to be secured by Letters Patent, is—

1. In a machine for manufacturing hat-linings, the combination of a pair of rolls the meeting surfaces of which are curved from 100 end to end and milled, one roll have a convex and the other roll a concave working surface, and means for actuating said rolls, substantially as described.

2. In a machine for manufacturing hat-linings, a pair of rolls milled upon their outer 105 engaging surface for crimping the margin of the lining, said rolls having their meeting surfaces inversely curved from end to end in combination with means for actuating one of 110 said rolls, and provision whereby one of said rolls may be heated and the proper temperature maintained during the operation of the machine, substantially as described.

3. In a machine for manufacturing hat-linings, the combination of a pair of crimping-rolls having their crimping-surfaces correspondingly curved from end to end, said surfaces being provided with matching corrugations for forming substantially radial crimps, 115 and matching beads and crimps, substantially 120 as and for the purpose described.

4. In a machine for manufacturing hat-linings, the combination with a pair of fluted rolls for the crimping of the margin of the 125 lining material, of a shaft on which one of said rolls is mounted, and means for adjusting the angle of said shaft, substantially as and for the purpose described.

5. In a machine for manufacturing hat-linings, the combination with a bed-plate, of a double standard comprising space members having vertical guideways, a vertically-adjustable cross-head slidingly mounted there-

in, and means for adjusting said cross-head, a pair of crimping-rolls, one of which is mounted on a substantially horizontal shaft and the other on an inclined shaft, said inclined shaft 5 being journaled in said cross-head whereby it is adjustable to its angle, substantially as and for the purpose described.

6. In a machine for manufacturing hat-linings, the combination with a bed-plate, and 10 a standard thereon, of a pair of crimping-rolls mounted on shafts extending at an angle to each other, one of said shafts being journaled in an adjustable cross-head movable up and down relatively to said standard, and a spring 15 interposed between said shaft and standard for maintaining the engagement between the crimping-rolls, substantially as described.

7. In a machine for manufacturing hat-linings, the combination with a bed-plate, and 20 a standard thereon, of a cross-head adjustable in said standard, a pair of crimping-rolls mounted on shafts extending at an angle to each other, one of said shafts being journaled in a cross-head and provided intermediate its 25 ends with an annular groove, a collar fitting loosely in said groove, and a contractile spring interposed between said collar and standard, substantially as and for the purpose described.

8. In a machine for manufacturing hat-linings, the combination with a bed-plate, and a 30 double standard comprising spaced members having substantially vertical grooves, of a cross-head having its ends slidingly fitted in said grooves, threaded rods engaging the opposite ends of said cross-head for moving the latter longitudinally of the slots, and a pair of crimping-rolls mounted upon shafts extending at an angle to each other, one of said shafts being journaled in the cross-head, substantially as described.

9. In a machine for manufacturing hat-linings, the combination with a bed-plate, and a standard thereon, of a pair of crimping-rolls mounted upon shafts extending at an angle 45 to each other and means whereby one of said shafts may be vibrated for moving the crimping-rolls apart, substantially as described.

10. In a machine for manufacturing hat-linings, the combination with a pair of crimping-rolls, and actuating means therefor, of an 50 elliptical support for the lining material, a bearing-head secured to the underside of said support and provided with a slot, a stationary disk on which said bearing-head rests and a pin or stud projecting from the face of said 55 disk and entering the slot in the bearing-head, whereby an eccentric motion is given to the lining-support, substantially as and for the purpose described.

11. In a machine for manufacturing hat-linings, a revoluble support for the lining material, and means for securing said material thereon, in combination with a bearing-head 60 secured to said support and provided with spaced flanges and also with a slot extending 65 transversely to said flanges, a stationary disk upon which said bearing-head is mounted and lying between said flanges, a pin or stud projecting from the face of the disk and working in the slot in the bearing-head, and provision 70 whereby said pin or stud may be adjusted, substantially as and for the purpose described.

12. In a machine for manufacturing hat-linings, in combination, a support for the lining material, a bearing-head secured thereto and provided with spaced flanges and a slot 75 extending transversely to said flanges, a stationary disk provided with a radial slot and having the bearing-head mounted revolvably 80 thereon, an adjustable slide-bar and securing means therefor, and a pin or stud carried by said bar and projecting through the slot in the disk and working in the slot in the bearing-head, whereby an eccentric motion is imparted 85 to said support, substantially as described.

In testimony whereof I have signed this specification in the presence of two subscribing witnesses.

WILLIAM HENRY THOMAS.
